UNITED STATES PATENT OFFICE.

CHARLES W. MUNZ, OF DETROIT, MICHIGAN.

CLOSING AND LOCKING DEVICE FOR EXTENSION-TABLE PEDESTALS.

No. 906,151.

Specification of Letters Patent.

Patented Dec. 8, 1908.

Application filed October 15, 1907. Serial No. 397,517.

To all whom it may concern:

Be it known that I, CHARLES W. MUNZ, a citizen of the United States of America, residing at Detroit, in the county of Wayne 5 and State of Michigan, have invented certain new and useful Improvements in Closing and Locking Devices for Extension-Table Pedestals, of which the following is a specification, reference being had therein 10 to the accompanying drawings.

The invention relates to extension tables of that type in which the central pedestal is formed of separable sections, and it is the 15 object of the invention to obtain a simple construction of mechanism for closing and locking said pedestal sections as hereinafter set forth.

In the drawings—Figure 1 is a perspective view of a portion of the pedestal and the 20 closing and locking device therefor; Fig. 2 is a vertical central section showing the members of the closing and locking device disengaged from each other; and Fig. 3 is a horizontal section showing one of the locking 25 members in plan view.

A and B are the respective sections of the pedestal of an extension table (not shown).

C is a hooked lever or rock arm pivotally secured at D to one of the sections, and E is 30 a coöperating member pivotally secured at F to the opposite section of the pedestal. The pivotal points of the members C and E are preferably in slightly different horizontal planes, so that when both are arranged 35 horizontally the member C will pass beneath the member E.

D' is a stop for normally holding the link E in a horizontal plane. The member E is provided with an eye E' for engagement 40 with the hook C' of the member C, and the length of said members is such that the hook will be brought into registration with the eye before the pedestal sections are completely drawn together. Thus, by raising 45 the lower member C it will be engaged with the eye, and in the further upward movement the members C and E will operate as toggle levers, drawing the two pedestal sections together.

For operating the member E a rod G is 50 connected therewith, which extends upward through the pedestal, and is connected at its upper end to a crank arm H on the rock shaft I. This rock shaft is journaled in 55 suitable bearings upon the table, and extends beneath the top thereof to a point near the

periphery for a convenient operation, where it is provided with an operating handle J. The parts are preferably so arranged that the pedestal sections will be drawn tightly 60 together as the crank H assumes a vertical position, and by then moving the crank slightly beyond the center against a fixed stop the parts will be locked from accidental disengagement. As illustrated, the rock 65 shaft is journaled in a sheet metal bracket K, having flanges L and M at opposite ends thereof apertured for the passage of the shaft, and the inner flange L has a struck-out portion N forming the stop for limiting the 70 movement of the crank.

With the construction as thus far described, in operation the table is closed by moving the sections thereof together in the usual way, but the pedestal sections are 75 seldom completely closed by this operation. To draw them together, the operator merely rocks the arm J to move the shaft I and crank H, the latter drawing upward on the rod G so as to cause the member C first to engage 80 its hook C' with the eye E' of the member E, and then to draw the said members in angular relation, whereby the pedestal sections are drawn together. As long as the parts are left in this position, the pedestal 85 sections will be held from separation, but at any time they may be released by a movement of the rock arm J, which will lower the member C and disengage it from the member E.

It is important that the adjustment of the 90 parts should be such as to draw the pedestal sections tightly together with the amount of movement imparted to the members C and E by the crank H. I therefore preferably provide an adjustment, and preferably 95 make the member E the adjustable one. As shown, this member consists of the eye portion E', which is provided with a threaded shank a engaging a correspondingly threaded aperture in a U-shaped member b, which 100 terminates in oppositely extending pivot portions c.

O is a bearing secured to the pedestal section A, and having grooves O' therein for the reception of the pivot portions c.

d is a lock nut for holding the shank a in any desired position of adjustment. Thus by loosening the lock nuts d the shank a may be adjusted inward or outward to alter the length of the member E.

What I claim as my invention is:

1. A closing and locking device for pedes-

- 5 tals comprising a pair of links respectively pivoted to said pedestal sections normally arranged in substantially parallel planes, means at the inner ends of said links for engaging each other, and means intermediate said pivotal points for moving said links when engaged in angular relation to draw said pedestal sections together.
- 10 2. A closing and locking device for pedestals comprising a pair of links having a detachable pivotal connection with each other and each being pivotally connected to one of the pedestal sections, means for holding said links normally in substantially parallel planes, and means connected to one of said links for engaging the same with the other link and for moving said links after such engagement out of parallel planes to draw said pedestal sections together.
- 15 20 3. A closing and locking device for pedestals comprising a link provided with an eye portion and a hooked rock arm respectively pivotally connected to the pedestal sections and normally arranged in different horizontal planes, a rod attached to said hooked rock arm extending upward through said pedestal, and means for drawing upward said rod to engage the hook with said eye and to draw the pedestal sections together.
- 25 30 4. A pedestal closing and locking mechanism comprising a pair of links normally arranged in substantially parallel planes respectively pivoted to the pedestal sections, means at the inner ends of said links for engaging each other, means intermediate the pivotal points of said links for engaging and disengaging the inner ends of said links and for moving them in angular relation to each other to draw the sections together, and means for adjusting the length of one of said links.
- 35 40 5. A closing and locking device for pedestals comprising a pair of links respectively pivoted to said pedestal sections normally arranged in different horizontal planes, means for adjusting the length of one of said links, a rod attached to one of said links intermediate its end and its pivotal connection

50 with the pedestal section extending upward through said pedestal, and means for drawing upward said rod to engage one of the links with the other, and to draw the pedestal sections together.

55 6. A closing and locking device for pedestal extension tables comprising a hooked member and an eye member pivotally connected respectively to the separable sections of the pedestal and adapted for engagement with each other, a rod extending upward through the pedestal for actuating said hooked member and connected thereto intermediate the ends of said member, a rock shaft journaled in bearings on the under side of said table top, a crank arm actuated thereby and connected to said rod, and a 60 stop on one of said bearings for limiting the movement of said crank slightly beyond the vertical position thereof.

65 7. A closing and locking device for pedestal extension tables comprising a pair of disengageable links respectively connected to the pedestal sections, a rod for actuating said links extending upward through the pedestal, a rock shaft having a crank arm thereon connected to said rod, and a bearing 70 for said rock shaft comprising a metal strip extending longitudinally of the shaft and having flanges at its opposite ends apertured for the passage of said shaft, and a lug struck outward from one of said flanges forming a 75 stop for limiting the movement of said crank.

80 8. A closing and locking device for pedestals comprising a pair of links respectively pivoted to said pedestal sections, means at the inner ends of said links for engaging each other, and means intermediate the pivotal points of said links for moving said links when engaged in angular relation to draw said pedestal sections together.

85 In testimony whereof I affix my signature 90 in presence of two witnesses.

CHARLES W. MUNZ.
